UNITED STATES PATENT OFFICE.

CHARLES S. DUNBRACK, OF SWAMPSCOTT, MASSACHUSETTS.

IMPROVEMENT IN BOOTS AND SHOES.

Specification forming part of Letters Patent No. 95,210, dated September 28, 1869.

To all whom it may concern:

Be it known that I, CHARLES S. DUNBRACK, of Swampscott, of the county of Essex and State of Massachusetts, have made a new and useful invention having reference to Shoes or Boots; and I do hereby declare the same to be fully described in the following specification, and represented in the accompanying drawings.

Figure 1 denotes a transverse section of a shoe-upper lasted, and having applied to it and the upper lasted on it a sole prepared in accordance with my invention. Fig. 2 is a top view; Fig. 3, a bottom view; and Fig. 4 a transverse section of a sole as it appears preparatory to being lasted.

My present invention consists in the outer sole as made with a groove or channel to receive the upper, such groove or channel being made in that face of the sole against which the upper is to abut; also, in the outer sole as made with such a groove in one face, and with a stitch-receiving groove in its opposite face, the whole being substantially as herein-after described.

In the drawings, the last is represented at A as recessed in its bottom or sole, as shown at a, to receive a false inner sole, b, provided with a series of spurs, e, extended from it, the whole being as represented and described in the specification and drawings of another application for a patent made by me, and to which my present application is auxiliary.

In Fig. 1, B exhibits the upper leather or upper, and C the outer sole of the shoe. The outer sole C I not only form with a lipped channel, d, to receive the sewing, such channel being in its outer face or tread; but on the opposite side I make within the sole, and around it and near its periphery, a groove, e. This groove is to enable the upper to be drawn into the sole by the sewing extending through the sole from the other groove, the same being to prevent the stitches from being seen or exposed when the upper is drawn upward from the outer sole. Furthermore, the groove is advantageous in other respects, or it operates to make a closed joint between the outer sole and the upper, and thus renders the sole more impervious to water.

I claim—

1. An outer sole as made with the upper receiving groove or channel e, arranged in that face or side of the sole which is to abut against the upper leather to be joined to the sole.
2. An outer sole as made with the sewing or stitch groove d in its outer face, and with the upper receiving-groove e in its inner or upper face, such grooves being arranged relatively or opposite to each other, in manner as represented.

CHARLES S. DUNBRACK.
